OUTDOOR GRILL

Lester E. Watson, P.O. Box 3307, Station A, Tyler, Tex.,
and Jasper L. Corley, 216 N. 54th St., Birmingham, Ala.

Filed July 7, 1959, Ser. No. 56,686

Term of patent 14 years

(Cl. D81—10)

What is claimed is:

The ornamental design for an outdoor grill, as shown.
